UNITED STATES PATENT OFFICE.

JOHN B. DAILEY, OF DETROIT, MICHIGAN, ASSIGNOR TO GENERAL MOTORS CORPORATION, OF DETROIT, MICHIGAN, A CORPORATION OF DELAWARE.

GRINDING AND POLISHING MACHINE.

Application filed February 18, 1924. Serial No. 693,562.

The invention relates to machines for grinding or polishing and while in some respects of more generic application it is especially concerned with machines designed for 5 preparing specimens for metallographic investigations.

At the present time it is customary to control or check the quality and characteristics of metals and alloys used for various industrial purposes and to determine the effect of 10 heat treatments and other operations affecting the internal structure of the metal by microscopic or photographic investigation of specimens showing the cross section of the 15 metal or article in question. For such investigations it is necessary that the specimens be very carefully ground and polished. Where extensive manufacturing operations are carried on as, for example, in a large 20 automobile manufacturing plant, it is not unusual for a single metallurgical testing laboratory to be required to prepare and examine hundreds of specimens daily, and the preparation of test sections with the necessary rapidity becomes a task of considerable importance. 25

The object of my invention therefore is, in general, to improve the construction and 30 operation of machines of the type used in producing smooth plain surfaces on objects usually of relatively small dimensions, and to facilitate the process of polishing, particularly where a large number of objects are to be operated upon.

Further objects and advantages will appear from the following description taken 35 in connection with the accompanying drawings illustrating one embodiment of the invention, and in which:

Fig. 1 is an elevation partly in section, showing a plurality of polishing units arranged for convenient operation and associated with suitable water supply and sewerage connections;

Fig. 2 is a plan view of one of the units; Fig. 3 is a vertical section on line 3—3 of Fig. 2;

Fig. 4 is a detail vertical section on line 4—4 of Fig. 3; and

Fig. 5 is a horizontal section on line 5—5 of Fig. 4.

Referring to the drawings, I have shown in Fig. 1 a group of three grinding or polishing units associated in a single assemblage, 55 which arrangement I have found highly sat-

isfactory for convenient and expeditious operation. The assemblage includes a stand or bench comprising frame members 10, 11 supporting a top 12, which may be of stone, wood, or other material suitable for the purpose. 60 The top 12 is provided with circular apertures within which may be mounted metal rings 13 for supporting the individual grinding or polishing units. The top is also provided with basins or wash receptacles 14 which may be connected to a pipe 15 leading to a suitable sewer connection. Each of the respective grinding or polishing units comprises a frame or bracket having a vertically extending portion 16 and a horizontal portion 17. The vertical portion 16 is shaped to receive the base 18 of an electric motor 19, the motor being secured to the bracket by screws or bolts 20. The armature shaft of the motor indicated at 21, therefore, extends 70 substantially in a vertical direction. 75

The horizontal portion 17 of the motor bracket is provided with a cup shaped portion 22 with an opening in the bottom through which extends a spindle 23. Surrounding 80 the spindle within the cup shaped portion 22 are arranged anti-friction lateral bearings 24, 25, and an anti-friction thrust bearing 26. Above the cup shaped portion 22 the spindle 23 is provided with a collar 27, the lower 85 surface of which serves as a shoulder to support the spindle and the parts carried thereby upon the bearings 24, 25 and 26. A felt washer 28 and a sheet metal cap 29 may be mounted upon the spindle above the anti-friction bearing, as shown, to cover the upper end of the cup shaped bearing receptacle 90 in the portion 22 and thereby protect the anti-friction bearings from dust, moisture, etc. A lubricant receptacle 30 may also be 95 provided communicating with the cup shaped bearing cavity to supply lubricant thereto as desired.

Above the collar 27 the spindle 23 is screw threaded as at 31 to fit a correspondingly 100 threaded hub 32 on the polishing disk or table 33. The table when in position on the spindle 23 is therefore supported in an approximately horizontal position, and when the spindle is driven by the motor 19 the table will be rotated in an approximately horizontal plane. It will be understood, however, that the exact 105 position of the table 33 may be varied to suit the convenience of the operator and the character of the work.

The upper surface of the table 33 will be provided with suitable means for performing the desired operation of grinding or polishing. In the form illustrated in the drawing 5 the table is provided with a fabric cover 34, which may be held in position by a hoop 35. The character of the fabric will depend upon the nature of the articles to be ground or polished, the character of the abrasive used, 10 and other conditions, as well known to those skilled in this art. In the assemblage of units illustrated in Fig. 1 it is preferred to use for the cover 34 of the first unit a coarse material such as canvas, while the cover 34' 15 of the second unit will be of a finer material, as of broadcloth, and the cover 34'' of the third unit of still finer material. Abrasives of corresponding degrees of fineness will of course be employed on the successive tables. 20 The horizontal portion 17 of the motor bracket is secured as by bolts 36 to the lower side of a casing member 37, of generally annular form which performs the function both 25 of a support and a shield. This member may be cast or otherwise formed of metal, and is provided at its periphery with a flange 38 which may be rigidly secured to the bench 12 or to the ring 13 as by screws 39. The bottom portion of the member 37 extends upwardly 30 as at 40 to form a sleeve surrounding the spindle 23 and preventing the overflow of water or other liquid within the member 37 around the spindle and its bearings. The upper edge of the member 37 is directed inwardly as at 41 to form a flange adapted to catch liquid or other material thrown against the outer walls of the shield and prevent the same from escaping over the upper edge of 35 the shield. At a suitable point in the bottom 40 of the shield is provided a drainage aperture 42, from which a pipe 43 leads to a suitable sewer connection, as illustrated in Fig. 1. The pipes leading from the successive polishing units are connected by a header 44 and a pipe 45 connection 45 to a drain pipe 15.

In order to transmit motion from the armature shaft 21 to the spindle 23 the said shaft is provided with a coupling sleeve 46 keyed to the armature shaft to rotate there- 50 with as at 47, and prevented from movement longitudinally of the shaft by set screw 48. An anti-friction bearing 49 may be provided between this coupling sleeve and the frame of motor 19, thereby assisting in supporting 55 the weight of the armature shaft and the parts mounted thereon. A similar coupling sleeve 50 is keyed as at 51 to the lower end of the spindle 23. A disk or ring 52 of flexible or yieldable material, as leather, is inter- 60 posed between the adjoining faces of the coupling disks or sleeves 46 and 50. Holes 53 are formed in the ring 52, and axially projecting pins 54, 55 are seated in apertures in the sleeves 46, 50, respectively, in position to 65 engage in the holes 53; the pins 54 carried

by sleeve 46 engaging in one pair of holes 53 on opposite sides of the spindle 23, while the pins 55 carried by sleeve 50 engage in the other pair of holes intermediate those in which the pins 54 engage. It will be seen, 70 therefore, that the transmission of motion from the motor shaft or the coupling sleeve 46 to the spindle 23 through the coupling sleeve 50 takes place through an intermediate flexible or yielding member, which serves to 75 relieve the parts of shock to a certain extent and also permits of assemblage without the accurate alignment of the spindle and armature shaft that would otherwise be required. It will be noted that the coupling provided 80 at the points 54, 55 and the flexible ring or disk 52 is of a readily detachable character, and hence the motor may be withdrawn from the spindle by endwise sliding movement 85 upon the removal of the securing means 20, and assemblage of the motor and spindle is also easily performed.

It will also be noted that the respective units comprising the supporting ring and shield 37 and the bracket 16, 17 with the parts 90 assembled thereon may be mounted upon the bench by merely inserting the assemblage from above into the apertures on the bench. The manufacture and assembling of the apparatus is, therefore, greatly facilitated since 95 the respective units can be assembled at the convenience of the workman in a machine shop or at the factory, and may then be readily installed at the place of use by ordinary unskilled workmen. At the same time the 100 parts may be readily disassembled for repair or replacement without requiring special skill.

When the operation performed upon the machine requires the supply of water or other liquid to the rotating tables 33, such liquid may be supplied by pipes arranged to discharge upon the surface of the tables. In the assemblage illustrated in Fig. 1, where water is utilized, pipes 56 may be mounted 105 upon the bench in position to discharge water upon the tables, the flow of water being controlled by valve means as at 57. The discharge portion of pipe 56 is preferably arranged to swing about the axis of the vertical portion so that the pipe may be positioned where it will not interfere with the grinding operation when a supply of liquid is not desired. Similar pipes 58 may be mounted 110 upon the bench in position to discharge water into the basins or receptacles 14, the water being supplied both to pipes 56 and 58 from a pipe 60 connected to a suitable source of supply 59. In the arrangement illustrated 115 the basins 14 and pipes 58 are arranged between the respective polishing units in such position that an operator engaged in polishing a specimen in one of the units may readily have access to one of the basins for the purpose of washing the specimen upon which 120 125 130

he is working. The provision of a plurality of units provided with polishing means of successive gradations of fineness and with abrasives of similar grades enables the work 5 of polishing a specimen to a desired extent to be carried out without necessitating any change in the nature of the polishing means, as would be necessary if the operation were performed upon a single polishing unit.

10 The arrangement further enables a number of workmen, for example, three in the assemblage illustrated, to engage at the same time upon the work of polishing specimens, each workman receiving the specimen from 15 the preceding workman, and thus enabling the successive operations to be completed most expeditiously.

10 The motor 19 may be controlled by any usual or suitable control devices. As illustrated current is supplied by conductors 61, the actuation of each motor being controlled independently of the others as by a switch 62. Additional means of usual character such as rheostats may be employed to vary at will the 25 speed of each motor.

While I have described herein specific details of construction, it will be understood that changes may be made without departing from the spirit and scope of the invention, 30 and therefore I do not desire to be restricted by reason of the specific disclosure, except as required by the language of the appended claims, in view of the prior art.

I claim:

35 1. In a polishing machine, a support hav-

ing an aperture therein, a shield member mounted upon said support and positioned in said aperture, a bracket secured to and depending from said member; a motor mounted upon said bracket, a rotatable table, and 40 means for driving said table from said motor, the bracket, motor, table and driving means being insertible or withdrawable as a unit with said member through said aperture.

2. In a grinding or polishing machine, a 45 shield member provided with means whereby it may be secured to a bench or stand, a bracket secured to and supported by said shield member, a table positioned within said member, a spindle adapted to support said table, 50 bearings for said spindle carried by said bracket and arranged to support the spindle wholly from the bracket, and a motor support by said bracket and operatively connected to said spindle.

3. In a grinding or polishing machine, a shield member provided with means whereby it may be secured to a bench or stand, a bracket supported by and depending from the 55 said member, a table positioned within said member, a spindle upon which said table is supported, bearings for said spindle carried by said bracket independently of the shield member, and an electric motor also carried by said bracket and having its armature shaft 60 approximately in alignment with said spindle, and operatively connected thereto.

In testimony whereof I affix my signature.

JOHN B. DAILEY.
